UNITED STATES PATENT OFFICE.

GEORGE H. PRENTICE, OF PAINESVILLE, OHIO.

DEVICE FOR PREVENTING THE CREEPING OF RAILS.

No. 832,699.

Specification of Letters Patent.

Patented Oct. 9, 1906.

Application filed June 30, 1906. Serial No. 324,252.

To all whom it may concern:

Be it known that I, GEORGE H. PRENTICE, a citizen of the United States of America, residing at Painesville, in the county of Lake and State of Ohio, have invented certain new and useful Improvements in Devices for Preventing the Creeping of Rails; and I hereby declare the following to be a full, clear, and exact description of the invention, such as will enable others skilled in the art to which it pertains to make and use the same.

This invention relates to improvements in means for preventing the creeping of rails.

15 The object of this invention is to provide an antirail-creeping device which is exceedingly simple and durable in construction and reliable in its operation and comprises two metal bars, with one of the bars adapted to be secured in place at one side of the rail and terminating in a wedge-forming member, which projects forwardly in the direction in which the rail tends to creep and is arranged with its larger end in front, and with the 20 other bar adapted to extend under and transversely of the rail and aforesaid wedge-forming member and provided with clamping-jaws at the ends, with one of the jaws clamping the wedge-forming member against the 25 base of the rail at one of the longitudinal edges of the base and with the other jaw clamping or gripping the other longitudinal edge of the rail-base, so that any tendency of the rail to creep will tend to pull the rail-clamping bar forwardly and tend to still further tighten the grip of the aforesaid jaws.

With this object in view this invention consists in certain features of construction and combinations of parts hereinafter described, and pointed out in the claims.

In the accompanying drawings, Figure 1 is a top plan of a rail provided with my improved means for preventing the creeping of the rail. Fig. 2 is a left-hand end view relative to Fig. 1 in section on line 22.

Referring to the drawings, A indicates the rail, and a the base of the rail.

B represents a tie arranged under and transversely of the rail and constituting a 50 rail-support.

G represents a metal bar which rests upon the tie at one side of the rail and extends transversely of the tie along the adjacent longitudinal edge of the base of the rail. The 55 bar G is spiked or otherwise secured to the tie, as at h.

The bar G terminates in a wedge-forming member g, which projects longitudinally of the rail in the direction in which the rail tends to creep and forwardly beyond the tie. 60

It is almost superfluous to remark that the rail tends to creep in the direction in which rolling-stock is intended to move on the rail, and the arrow c, marked upon the rail in Fig. 1, indicates the direction in which 65 the rolling-stock travels.

The wedge-forming member g is arranged with its larger end in front and bears against and clamps or grips the base of the rail at the adjacent longitudinal edge of the base. 70

K indicates a rail-clamping bar, which is arranged forward of the tie and parallel or approximately parallel with the tie. The bar K extends under and transversely of the rail and aforesaid wedge-forming member 75 and is provided at one end with a jaw k, which projects upwardly at the outer side of and embraces the wedge and grips and clamps the wedge against the base of the rail. Hence the jaw k and wedge-forming member 80 g clamp the rail at one of the longitudinal edges of the rail-base, and the bar K is provided at its opposite end with a jaw K', which clamps or grips the other longitudinal edge of the rail-base. 85

It will be observed that the tendency of the rail to creep in the direction indicated by the arrow c tends to pull the bar K forwardly from the tie, and consequently in the direction required to further tighten the wedge-forming member g between the jaw k and the rail, so as to tighten the grip of the jaws of the rail-clamping bar K. 90

What I claim is—

1. The combination, with a rail, and a tie 95 arranged under and transversely of the rail, of a bar arranged upon and transversely of the tie at one side and longitudinally of the rail, which bar is attached to the tie and has a wedge-forming member which projects beyond the tie in the direction in which the rail tends to creep and is arranged with its larger end in front, which wedge-forming member bears against the adjacent longitudinal edge of the base of the rail at the aforesaid side of the rail, and a rail-clamping bar arranged under and transversely of the rail and aforesaid wedge-forming member forward of the tie and provided at one end with a jaw arranged at the outer side of and embracing the aforesaid wedge-forming member and instrumental in clamping the latter against the 100 105 110

aforesaid longitudinal edge, said rail-clamping bar being provided at its opposite end with a jaw which clamps or grips the other longitudinal edge of the rail-base so that any tendency of the rail to creep will tend to pull the rail-clamping bar forwardly and tend to still further tighten the grip of the jaws of the said bar.

2. The combination, with a rail, and a tie
10 arranged under the rail, of a bar arranged upon the tie at one side of the rail, which bar is attached to the tie and has a wedge-forming member which projects in the direction in which the rail tends to creep and is arranged with its larger end in front, which wedge-forming member bears against the base of the rail at the aforesaid side of the rail, and a rail-clamping bar arranged under and transversely of the rail and aforesaid 15 wedge-forming member and provided at one end with a jaw which clamps the said wedge-forming member against the base of the rail at the aforesaid side of the rail, said rail-clamping bar being provided at its opposite 20 end with a jaw which clamps or grips the rail-base at the opposite side of the rail so that any tendency of the rail to creep will tend to pull the rail-clamping bar forwardly and tend to still further tighten the grip of the 25 jaw of the said bar.

3. The combination, with a rail, and a tie
arranged under the rail, of a bar secured to the tie and having a wedge-forming member which projects in the direction in which the rail tends to creep and is arranged with its larger end in front, which wedge-forming member bears against one of the longitudinal edges of the base of the rail, and a rail-clamping bar arranged under and transversely of the rail and aforesaid wedge-forming member and provided at one end with a jaw which 35 clamps the wedge-forming member against the aforesaid longitudinal edge of the rail-base, said rail-clamping bar being provided 40

at its opposite end with a jaw which clamps 45 or grips the other longitudinal edge of the rail-base so that any tendency of the rail to creep will tend to pull the rail-clamping bar forward and tend to still further tighten the grip of the jaws of the said bar. 50

4. The combination, with a rail, of a suitably-supported bar arranged at one side and longitudinally of the rail, which bar projects in the direction in which the rail tends to creep and is arranged with its larger end in front, which wedge-forming member bears against the base of the rail at the aforesaid side of the rail, and a rail-clamping bar arranged under and transversely of the rail and aforesaid wedge-forming member and provided at one end with a jaw which clamps the wedge-forming member against the rail-base, 55 said rail-clamping bar being provided at its opposite end with a jaw which clamps or grips the rail-base at the opposite side of the rail so that any tendency of the rail to creep will tend to pull the rail-clamping bar forwardly and tend to still further tighten the grip of the jaws of the said bar. 60

5. The combination, with a rail, and a tie
arranged under the rail, of a bar arranged upon the tie at one side and longitudinally of the rail, which bar is attached to the tie and has a wedge-forming member which projects in the direction in which the rail tends to 75 creep and is arranged with its larger end in front, which wedge-forming member bears against the adjacent longitudinal edge of the base of the rail, and means whereby the said wedge-forming member is caused to more tightly grip the rail by any tendency of the rail to creep. 80

In testimony whereof I sign the foregoing specification in the presence of two witnesses.

GEORGE H. PRENTICE.
